UNITED STATES PATENT OFFICE.

CHARLES HALL RODEMER, OF TOPEKA, KANSAS.

GIRDER OR ARCH.

SPECIFICATION forming part of Letters Patent No. 374,271, dated December 6, 1887.

Application filed October 1, 1887. Serial No. 251,252. (No model.)

To all whom it may concern:

Be it known that I, CHARLES HALL RODEMER, of the city of Topeka, county of Shawnee and State of Kansas, have invented a new and useful Corniced Girder or Arch, of which the following is a specification.

My invention relates to a girder or arch for the support of the fronts of buildings, having a cornice front or face cast solid to the girder, thereby saving the expense and annoyance so usual in the construction of cornice to give finish to the fronts of buildings by the old method. Besides, having the face solid with the girder adds greatly to its strength and solidity.

My invention can also be used for bridges or to span any open space requiring great weight to be supported.

Figure 1 is a front view showing the cornice front or face in straight lines and the girder or arch in dotted lines. Fig. 2 is a front view, and Fig. 3 a rear view, of my cornice; and Fig. 4 is a transverse section.

Similar letters refer to similar part in the drawings.

The bottom and top plates of the girder may be constructed any length or breadth that may be required and made of cast-iron. Said bottom and top plates are shown in accompanying drawings in dotted lines, and marked A.A. The angling braces are set between the top and bottom plates at an angle of about forty-five degrees; or they may be put in at right angles with plates. Said braces are shown in dotted lines, and are marked respectively, B.B. The cornice-front of said girder can be finished with any ornamentation (marked E) that may suit the taste or fancy of builders.

Having fully described my invention, what I claim as new, and desire to secure by Letters Patent, is—

The girder or arch proper, constructed substantially as described, in combination with the cornice-face, the parts being solidly connected in the process of construction.

CHARLES HALL RODEMER.
